J. SHEA

SHINGLING METHOD

Filed April 16, 1924

INVENTOR
John Shea
BY
Geo. H. Beeler
ATTORNEY

UNITED STATES PATENT OFFICE.

JOHN SHEA, OF NEW YORK, N. Y.

SHINGLING METHOD.

Application filed April 16, 1924. Serial No. 706,831.

To all whom it may concern:

Be it known that I, JOHN SHEA, a citizen of the United States, residing at New York city, borough of Manhattan, in the county of 5 New York and State of New York, have invented certain new and useful Improvements in Shingling Methods, of which the following is a specification.

This invention relates to the laying of 10 shingles and has particular reference to an improved method of laying shingles whereby a neat and tight roof may be secured with the minimum quantity of fasteners without an excess use of shingle material, through 15 an interlocking arrangement of the shingles so disposed as to eliminate spaces between the adjacent shingles for the sake of a tight roof as aforesaid.

With the foregoing and other objects in 20 view the invention consists in the arrangement and combination of parts hereinafter described and claimed, and while the invention is not restricted to the exact details of construction disclosed or suggested herein, 25 still for the purpose of illustrating a practical embodiment thereof reference is had to the accompanying drawings, in which like reference characters designate the same parts in the several views, and in which—

30 Figure 1 is a plan view of a preferred form of my shingle.

Fig. 2 is a fragmentary plan view of my shingle arrangement.

Fig. 3 is a sectional detail of an incomplete 35 assemblage on the line 3—3 of Fig. 2.

Fig. 4 is a sectional detail on the line 4—4 of Fig. 2.

Fig. 5 is an enlarged perspective view indicating at one end a finished joint and at 40 the other end a shingle distorted to show the structure normally covered by the lower point of a shingle.

Referring now more specifically to the drawings I show a plurality of similar or 45 uniformly sized shingles 10 each having an open ended slot 11 near one of its corners substantially perpendicular to the adjacent edge of the shingle from which the slot is formed, thereby constituting the corner portion of the shingle a locking tongue 12. As indicated in Fig. 1, the slot extends from the aforementioned edge of the shingle substantially to the adjacent diagonal 10' of the shingle.

50 S indicates a starting strip consisting of a

uniform oblong sheet of preferably the same material as the shingle, said starting strip serving the purpose of affording an interlocking connection between the shingles of the first course through the medium of the locking tongues and to aid in the ready and uniform laying of the first course, as well as to give sufficient body to this part of the roof covering.

55 Shingles of the first course are indicated by reference letters A and the various shingles of the course are designated by corresponding numerals from 1 to 6. Likewise for the sake of definite description, succeeding courses are indicated by the letters B 70 and C, the shingles of the different courses being correspondingly identified by numerals.

The first course of shingles is laid so as 75 to engage with the starting strip at the slotted corner, the locking tongue 12 of each shingle being passed beneath the starting strip by deflecting said locking tongue downward slightly out of the plane of the shingle. When the shingle is engaged as described 80 and the diagonal 10' registers with the upper edge of the starting strip, the starting strip will be received to the full extent of the slot, and the corner 13 adjacent to the slot will likewise engage with the top surface 85 of the starting strip. As shown by the drawings, although obviously the method is not limited to that particular representation, each right hand shingle of the first course overlaps the adjacent left hand shingle so 90 as to abut against the corner of the main body of the shingle and constituting the lower edge 13 of the slot 11, substantially throughout its length. A shingle course of 95 substantially even or flat top surfaces is thus formed, adapted to receive the next upper course for a tight joint. More specifically, it will be noted that shingle A² is laid as above described to overlap the tongue of shingle A¹, after which shingle A³ is laid in 100 corresponding manner to overlap the tongue of shingle A², and so on in succession for the entire first course.

The second course of shingles is laid in 105 symmetrical position relative to the first, the slotted corner of a shingle being engaged with the adjacent side corner of a shingle in the first course as shown best at the upper right edge of Fig. 2. Each shingle of the second course is moved downward over the 110

correspondingly numbered shingle of the preceding course so that the lower corner portion 15 thereof will overlap and cover and seal the slot 11. More specifically, 5 shingle B¹ is now interlocked with shingle A² by depressing the tongue of B¹ and passing the same beneath A², the lower exposed corner 15 of B¹ being so placed as to overlap the slot in shingle A¹. Shingle B² is now 10 interlocked in the same manner with shingle A³ and offset the same distance relative to A³ as shingle B¹ is to A² so as to cover the slot in shingle A² and to abut against the edge or corner 13 of the slot in shingle B¹. 15 The successive shingles in the second course are laid in the same manner.

A U-fastener or two-pronged nail 14 is then used to secure the four overlapping corners to the roof, the legs of the fastener 20 being positioned at the sides of the slot so that the fastener will span or straddle the same and effectively prevent any possible curling of the corners. It will be noted that but one fastener need be used for each 25 shingle and that each fastener passes through four shingles.

The third and succeeding courses may then be laid in turn in the same manner as the second. While I have indicated a square 30 form of shingle with an exposed oblong due to the overlapping or offsetting of each shingle more to the left than to the right, I do not intend to be limited unnecessarily to the specific form or disposition of the 35 shingles so illustrated.

I claim:

1. The herein described method of laying shingles which consists in laying rectangular shingles in courses substantially parallel to 40 the lower edge of the roof, the adjacent shingles of the adjacent courses lying in rows at an oblique angle with said edge of the roof; a corner portion of a shingle being slotted to form a tongue to pass beneath the 45 side portion of the adjacent shingle in the next lower course, a shingle in the oblique row of the second mentioned shingle being positioned so as to abut against an edge of said slot opposite said tongue of the first

mentioned shingle, and a shingle in the 50 oblique row of the first mentioned shingle overlapping the side portion of the third mentioned shingle so as to cover and render said slot weather tight.

2. The method of laying shingles wherein 55 rectangular shingles are laid in horizontal courses substantially parallel to the lower edge of the roof, corresponding shingles in the adjacent courses lying in oblique rows relative to said edge of the roof, each of 60 said shingles having a slot in a corner portion running inward from an edge at a uniform angle and position in the different shingles so as to form a tongue, each shingle of a course being adapted to receive in its 65 slot the side of an adjacent shingle in the next lower course by overlapping the side of said adjacent shingle while said tongue passes therebeneath, an adjacent shingle in the horizontal row of the first mentioned 70 shingle and in the oblique row of the second mentioned shingle being placed so as to abut against the slot edge of the aforementioned overlapping side of the first mentioned shingle, and a shingle in the next upper 75 course and in the oblique row of the first mentioned shingle being placed so as to interlock with the third mentioned shingle and to overlap the aforementioned slot edge.

3. The method as in claim 2 wherein a starting strip is placed substantially parallel to said edge of the roof and the first course of shingles is placed thereon so that the tongues thereof will pass beneath the upper edge of the starting strip to interlock with the same, each shingle of said course overlapping the adjacent shingle of the course so as to abut against said slot edge forming a uniform top surface adapted to receive the 80 second course for a weather-tight joint.

4. The method as in claim 2 including a 85 double pointed fastener for attaching the shingles to the roof, so positioned that the points thereof will pass at each side of the 90 slot through said shingles.

In testimony whereof I affix my signature.

JOHN SHEA.
